UNITED STATES PATENT OFFICE.

MAURICE LEVISON, OF CHICAGO, ILLINOIS, ASSIGNOR TO CHICAGO SIGNAL COMPANY,
OF CHICAGO, ILLINOIS, A CORPORATION OF ILLINOIS.

SELECTIVE SIGNAL-TRANSMITTER.

1,085,142.

Specification of Letters Patent.

Patented Jan. 27, 1914.

Application filed January 3, 1913. Serial No. 739,971.

To all whom it may concern:

Be it known that I, MAURICE LEVISON, a citizen of the United States, residing at Chicago, in the county of Cook and State of Illinois, have invented certain new and useful Improvements in Selective Signal-Transmitters, of which the following is a specification.

My invention relates to improvements in selective signal transmitters and has for its general object to provide a simple, easily operated, and efficient device which may be set and operated to transmit groups of electrical impulses indicative of selected plural-digit number signals.

For many purposes, such as transmission of alarm signals, call signals, and the like, it is desirable to employ a transmitter which may be set or adjusted to transmit electrical impulses indicating different number signals, instead of using a different transmitter, or different transmitter-wheel, for each signal.

One of the objects of my invention is to provide a device of the character described which will be small, compact, simple, and not liable to get out of order.

Another object of my invention is to provide a device of the character described in which the transmitter, when started in signaling operation normally operates to transmit its set signal a plurality of times, but wherein the transmitter may be stopped after any round of its operation, the stop always occurring after the completion of a round of signals, so as not to interrupt the transmission of a full signal on any round.

In the drawings wherein I have illustrated an embodiment of my invention Figure 1 is a plan view of the transmitter with the cover removed; Fig. 2 is a side elevation of the transmitter with the cover removed; Fig. 3 is a small plan view of the complete device; Fig. 4 is a transverse section taken on line 4-4 of Fig. 2; with the cover in place; Fig. 5 is a horizontal section on line 5-5 of Fig. 6; Fig. 6 is a vertical sectional view taken on line 6-6 of Figs. 1 and 4; Fig. 7 is an inverted plan view of the top plate, showing the movable contact arm in relation thereto; Fig. 8 is a detail view of the adjustable selector members in one relation; Fig. 9 is a diagram of the circuit connections.

In the drawings, the circular bottom plate 15 carries an insulating ring 16 and four vertical posts 17 of a frame the upper mem-

ber of which is provided by a horizontal insulating plate or base 19. Between these upper and lower plates 15-19 is mounted a motor structure 20, to be described, serving to drive an arm 21 mounted on a central shaft, said arm bearing at its extremity the contact finger 22 pressed upwardly by a spring 23 so as to contact with the under face of the insulating plate 19, and with certain fixed contacts carried by said plate.

Upon the plate 19 in the path of movement of the contact finger 22 I arrange groups of contacts, of which two are shown at 25 and 26, these representing respectively the "tens" group and the "units" group. Each of these contacts, as is best shown in Fig. 6, comprises a pin 27 and a head 28, the pin extending through the insulated plate 19 so that its lower surface lies in a path of movement of the movable contact 22, and the head providing a spring bend 29 and a transversely folded crest 29' so that the upper portion of each stationary contact member has considerable resiliency. For convenient cooperation on different arcs with the selector parts to be described the heads of the contacts of the tens group, 25, are turned radially outward and those of group 26 radially inward with respect to the arc on which all of the pins 27 are placed, so that the heads of contacts 25 are at a greater distance from the center of the device than those of contacts 26. Upon the plate 19 I mount two adjustable selector parts, one for each group of contacts 25 and 26, and each movable to make electrical contact with the heads of any desired number of said stationary contact parts.

Specifically 30 indicates a shaft mounted centrally of the insulating plate 19. On this shaft are mounted for rotation the two movable selector members 31 and 32, arranged independently to be oscillated. One of these members 31 is shiftable to make contact with the heads of any desired number of the contacts of the "units" group 26 and the other member is similarly shiftable for electrical connection with the heads of any desired number of contacts in the group 25 or "tens" group. As diagrammatically shown in Fig. 9 these two shiftable selector members 31 and 32 are electrically connected with the same side 33 of a line circuit (shown conventionally as a bell-circuit) and the movable contact point 22 is electrically connected with 110

the other side 34 of said circuit so that in its rotation the movable contact 21 will close the circuit at each pin 27 of contact groups 25 and 26 that is electrically connected with the other side of the line through the intermediary of the shiftable selectors 31 and 32. For connection of the instrument in circuit, binding posts 35 and 36 are provided one wired at 37 to the motor frame and the other 10 wired at 38 to shaft 30. In the specific construction shown (see Fig. 8) the selector member 31 preferably takes the form of a plate of smaller diameter with a contact wing extension 39 for contact with the contact heads 28 of group 26. This plate is carried by a sleeve 40 on the shaft 30 said sleeve at its upper end bearing a turning knob 41. The under side of plate 31 has therein recesses 42 coöperating with a 20 "click" or spring latch 43 mounted in a small housing projecting from plate 19, so that the plate clicks forward from hole to hole (42) as the wing 39 progresses from one fixed contact to another. The other 25 plate 32 is attached to and carried by a finger piece 45 rotatably mounted on the sleeve 40, a washer 46, being interposed between the two plates 31 and 32. Plate 32 extends out beyond plate 31, except where it is cut 30 away at 47 and it has an extended contact wing 48 extending out beyond the wing 39 of the lower plate 31 and having a down-turned flange 49 for contact with the heads of stationary contact of "tens" group 25. 35 Plate 32 has therein a series of recesses 50, for coöperation with appropriate click latch 51.

Suitable stops for limiting the movement of the two plates to ranges appropriate to 40 their contact making operations may be provided in any suitable fashion, and indicating means are provided for ready visual indication of the position of the two selector members in order that the device may readily be set to send any desired signal. For 45 this reason the casing 60 which covers the frame and motor mechanism has formed therein two sight apertures 61 and 62, respectively, appropriate to the tens and units 50 indications. Selector part 31 has secured thereto a spacer block 53 carrying a rotary dial 54 bearing units indices and selector plate 32 has secured thereto a concentric arcuate dial bearing tens indices, the arrangement being such that the numbers displayed through the casing openings indicate the numbers for which the selector is set.

It will be observed, with respect to Fig. 1, that progressive inclusion of the tens contacts of the group 25 requires counter clockwise movement of the selector part 32, whereas similarly progressive inclusion of the contacts of units group 26 requires clock-wise movement of the part 31. This is done in 55 order that the moving electrical contact 22,

sweeping in a clock-wise direction, may always pass from the last energized contact of the tens group 25 to the first energized contact of the units group 26 in the same length of time, so that the interval between the tens group and the units group in the audible signaling shall always be the same. 70

The motor for driving in rotation the contact arm 21 is preferably of a manually-wound spring variety. Its mechanism is 75 carried between two plates 70 and 71 supported by the posts 17. The general construction of such a spring motor mechanism is so well understood that its general features need little description. The winding handle 75 is connected with a large gear 76 which operates through speed increasing gears 77 and 78 to turn the winding shaft 79 for main spring 80, which, when wound, actuates a suitable gear train, including an intermediate gear 81 on the central shaft 82 whereon the arm 21 is mounted, said gearing continuing through an accelerating train to the shaft 83 of a suitable centrifugal governor 84 regulable as to its speed by an adjustable stop 85. This stop is in the form of a spring yoke adjustable by the screw 86 and having its active end bearing on a brake plate 87 secured to and rotatable with that end of the governor structure which 90 moves lengthwise of the shaft under changes of speed. The motor is wound by moving the handle in a clock-wise direction through a relatively few degrees of displacement and manifestly the motor will continue to run 100 until the spring is unwound, unless the motor be earlier stopped.

I provide, preferably, means automatically to stop the motor after a predetermined number of rotations of the shaft 82 105 and means whereby the motor may be stopped at will at the completion of any then-occurring cycle of rotation of said shaft 82.

In order to insure that the motor, when 110 once fully wound and started in operation, shall stop after a predetermined number of revolutions of the shaft 82 which carries the rotating contact arm, and shall stop always with the contact arm 21 in predetermined 115 position, I provide stopping means comprising a brake 90 arranged to bear on the periphery of plate 87, said brake being spring pressed toward the edge of the plate by spring 91. The shaft 92 which carries said 120 brake 90 has projecting therefrom two arms 93 and 94. The controlling arm 94 is adapted to coöperate with the edge of a disk 95 mounted on the shaft 82, said disk having in its periphery a notch 96 into which the extremity of arm 94 must descend in order that the acting end of brake 90 may coöperate with its disk on the governor shaft. When the motor is fully wound an arm 97 (see Fig. 5) moved by the operating handle 125

strikes a lever 98 which is secured to the shaft 92 of the brake. This rocks the shaft 92, throwing the brake out of contact with the disk 87 on the governor and also drawing 5 the controller arm 94 out of the notch in its disk 95 which is on the contact carrying shaft 82. When the latch is thus moved its locking arm 93 is engaged by a catch 99 pivoted on the frame, said catch having a releasing arm 100 which extends over into the path of movement of a pin 101 carried by the wheel 77 which moves in fixed ratio to the gear 76 of the winding lever 75. The parts are so proportioned that shaft 82 receives a 10 predetermined plurality of rotations—say six in number—while the pin 101 on gear 77 is moving from its initial position,—taken when the winding lever 75 is moved to fully wound position,—to the position in which it 15 trips the latch 99 to disengage it from the locking arm 93. The pin 101 releases the catch 99 just before notch 96 registers with the controller arm 94. Consequently it will be apparent that when the motor is fully 20 wound and arm 97 throws the brake out of coöperation with the disk on the governor shaft the motor may run its full course to turn the shaft 82 six times before the pin 101 trips out of the latch 99 and permits 25 trolley arm 94 to fall in the recess 96 thereby allowing spring 91 to force the brake 90 against the governor disk to stop the motor. It is desirable that the operator may be 30 able to stop the motor at pleasure, subject 35 however to the motor completing the then current cycle of rotation of the shaft 82, in order that no signal in course of transmission shall be abbreviated. To this end I provide on the catch 99 a second releasing 30 arm 103 having an inclined surface 104 with which coöperates a vertical plunger 105 extending upwardly through the top of the casing and normally retained in raised position by the spring 106. After the operator 40 has wound the transmitter and has started it in motion the plunger 105 may at any time be depressed, its lower active end acting on the inclined surface 104 to force over the latch 99 to such position that it releases arm 45 93. Spring 91 thereupon forces the controller arm 94 into contact with the periphery of the disk 95, but the torque of shaft 82 is so great that this pressure has no noticeable effect. The motor continues to operate until 50 the completion of a cycle of rotation of arm 21 when notch 96 registers again with the controller 94 and said arm, dropping into said notch, allows the brake to be thrown into contact with the disk 87 of the governor. 55 In résumé it will be seen that as the operator turns the knob 45 to bring the tens numerals 1, 2, 3, 4, successively into view at the tens opening 61 in the cover plate, the selector member 32 will correspondingly 60 have its downturned flange moved counter- 65 clockwise over the heads 28 of contacts in group 25 to connect one, two, three, or four,—as the case may be,—of the contact points of said “tens” group in electrical connection with binding post 36 for one side of the signaling line and then as the operator moves the other knob 41 oppositely or clockwise the selector member 31 will be advanced to make electrical connection between the same side of the signaling line and the 70 heads of a number of contacts of units group 26 corresponding with the numerical indication displayed through the units opening 62 of the casing. Accordingly, to set the signal, the operator has only to move the knobs to display the desired numbers. The operator then throws the handle 75 from dotted line position to full line position (Fig. 3) to wind the motor, which, in the exemplification shown, will rotate the contact arm 22 six times before the motor automatically stops. During each rotation of the contact arm 21 its contact point travels over all of the pins 27 exposed on the under surface of the insulating plate 19, but only 75 those pins whose heads 28 are connected in circuit by the selector plates 31 and 32 are “live” and accordingly the line circuit will be closed and opened appropriately to send that number signal which is indicated by the 80 setting of the instrument. It will be apparent that the number signal will be repeated six times if the motor be allowed 85 fully to run down, but since the parts employed to set the signal are not rotated, and 90 a considerable interval of time elapses between the completion of one signal round and the commencement of the next, it is easy for the operator to change the setting 95 between rounds if so desired, so that a different signal may be set for each signal 100 round if desired. Furthermore when a signal has been repeated as many times as the operator thinks necessary, less than the total 105 number, the operator may stop the motor 110 operation at the completion of any then current signal round by depression of the plunger 105 the operation of which to stop the motor has heretofore been described. 115 While I have herein described in some detail a particular embodiment of my invention which I believe to be advantageous in many of its details, and some details of which I may therefore claim, I do not desire to be understood to limiting my invention 120 to the specific construction described further than is specified in the claims and it will be apparent to those skilled in the art that many changes might be made in the embodiment of my invention without departure from the spirit and within the scope 125 of the appended claims. 130

What I claim is:

1. In a transmitter of the character described, the combination of a frame bearing

an insulating plate; a series of stationary contacts, normally disconnected from a circuit, carried by said insulating plate and extending therethrough; rotatable selector means carried by said plate on one side thereof, coöperating with one exposed portion of said fixed contact and movable to connect any selected number of said fixed contacts; means to connect said selector member in a circuit; a rotatable contact facing the opposite side of said insulating plate; motor means for moving said movable contact through several cycles, on each cycle successively to connect it with the several stationary contacts; means to connect said movable contact in circuit; a casing inclosing the motor, contact, and selector parts; means for stopping said motor at the conclusion of any cycle, including a controlling part extending to the exterior of the casing; and means for setting the selector extending to the exterior of the casing.

2. In a transmitter of the character described, the combination of an insulating structure; a plurality of contacts fixed thereon and arranged in groups, each contact having two exposed portions, one exposed portion of all of the contacts of the plurality of groups being arranged in the same line, the remaining exposed portion of each contact comprising an eccentric head, said heads turned to different positions for arrangement in lines which are different for the different groups; a movable contact operating in the line common to the exposed portions of all of the fixed contacts; means for moving said movable contact to bring it into connection successively with all of the contacts of said plurality of groups; a selector member for each group respectively, operating in the lines of the remaining exposed portions of the contacts of said groups, and movable to connect a selected number of the contacts of its group; and means for connecting the movable contact and the selector members in an electric circuit.

3. In a transmitter of the character described, the combination of an insulating structure; a plurality of contacts extending therethrough and arranged in groups, said contacts of the several groups on one side of said structure being exposed in a line, and on the other side of said structure having similar eccentric heads differently disposed to lie in a different line for each group, each said head consisting of a folded spring-member; a movable contact working on one side of said insulating structure in the line common to the contacts of said several groups; means for rotating said movable contact to bring it into connection successively with all of the contacts of said several groups; selector members, for each group respectively, on the other side of said insulating

structure arranged to work respectively on the lines of the heads of the contacts of said groups; means for moving each selector member to contact with and connect a selected number of the contacts of its group; and means for connecting the movable contact and the selector members in an electric circuit.

4. In a transmitter of the character described, the combination of a casing and, within said casing, a motor, a movable contact driven by said motor, an insulating plate above said motor, contacts extending through said insulating plate arranged in two groups in the path of movement of said movable contact, two selector means above said plate each movable to connect together a selected number of the contacts of its group, means extending to the exterior of the casing for operating said selector members in opposite directions from the proximate ends of their groups, and means for connecting the movable contact and the selector member in an electric circuit.

5. In a device of the character described, the combination of relatively shifttable contact members, a motor for driving one said relatively movable contact member provided with a relatively slowly moving rotary part, and a relatively rapidly moving rotary part, a brake for the last said part, and means on the slowly moving part for controlling the brake.

6. In a transmitter of the character described, the combination with relatively stationary and relatively movable contact parts, of a motor for driving said relatively movable contact parts, said motor comprising a driving spring, a winding handle therefor, a train driven from the driving spring, stop-means for preventing rotation of said train, means controlled by the winding handle for latching said stop means in inoperative position, and manual means for releasing said latching means.

7. In a transmitter of the character described, the combination with relatively stationary and relatively movable parts, of a motor for driving a relatively movable part comprising in combination an actuating spring, means to wind the same, a train driven from said spring, means to stop said train, a latch for holding said stopping means in motor releasing position, automatic means moving in harmony with movements of the winding handle for latching and unlatching said holding means for automatic starting and stopping of the motor, and manual means for moving said latching means to unlatching position to stop the motor.

8. In a device of the character described, the combination of relatively movable and relatively stationary contact parts, a motor for driving said relatively moving means

through a predetermined plurality of cycles, motor stopping means, means automatically controlling said motor stopping means, to permit its operation only at the completion 5 of a cycle of operation of the circuit closing means, for latching said motor stopping means in disabled position, means controlled by the motor automatically to move said motor stopping means to latched position 10 and to release the latch, and manual means for releasing said latch.

9. In a transmitter of the character described, the combination of a plurality of stationary contacts normally disconnected 15 from a circuit, a movable contact for connection in a circuit, means for moving said movable contact through several cycles, on each cycle successively to connect it with the several stationary contacts, means for 20 stopping said motor at the conclusion of any cycle, and selector means for connection in said circuit, coöperating with said fixed con-

tacts and movable to connect in the circuit any selected number of said contacts.

10. In a transmitter of the character de- 25 scribed, the combination of two groups of fixed contacts, a movable contact, means for moving said movable contact into successive connection with all of the fixed contacts, selector parts adjustable for electrical connection with selected numbers of said contacts of their respective groups, means for moving said selector parts oppositely whereby the connected contacts are located at contiguous ends of the two groups, and means 30 for connecting the movable contacts and said selector members in an electric circuit.

In testimony whereof I hereunto set my hand in the presence of two witnesses.

MAURICE LEVISON.
